UNITED STATES PATENT OFFICE.

LAWRENCE E. BRILL, OF COLUMBUS, OHIO, ASSIGNOR TO THE JEFFREY MANUFACTURING COMPANY, OF COLUMBUS, OHIO, A CORPORATION OF OHIO.

CHAIN.

Application filed October 8, 1924. Serial No. 742,430.

To all whom it may concern:

Be it known that I, LAWRENCE E. BRILL, a citizen of the United States, residing at Columbus, in the county of Franklin and State of Ohio, have invented new and useful Improvements in Chains, of which the following is a specification.

The present invention relates to chains, and has for its object to provide a chain composed of links of such construction that they may be readily assembled and disassembled for adjustment of chain links, or for replacement and repair, by unskilled workmen, and without the use of tools.

15 The invention is here shown and described as a chain designed particularly for use with sprocket wheels in power transmission, but it will be understood that the disclosure herein is illustrative and in no sense restrictive, 20 as the invention may be applied to chains other than transmission chains, and still be within the range of my invention.

In order that the invention may be clear to those skilled in the art, I have shown, in 25 the accompanying drawings, one embodiment thereof, in which drawings

Fig. 1 is a plan view of the preferred embodiment of my invention.

Fig. 2 is a side elevation of the chain 30 illustrated in Fig. 1.

Fig. 3 is a perspective detail of the separable coupling link of my improved chain.

Fig. 4 is a perspective detail of the strap link adapted to use with the coupling links.

35 Referring to the drawings by numbers, like numbers indicating like parts in the several views, my improved chain consists of strap links joined by coupling links of peculiar and novel construction. The strap links are endless loops 1, formed of suitable material, as, for example, steel bar stock of rectangular cross section, having bearing seats 2, preferably semi-cylindrical in form, at their ends.

45 Each coupling link consists of two similar, oppositely positioned side bars 3 from one end of each of which projects a pintle 4 adapted to extend through the adjacent strap link 1 and to bear upon the semi-cylindrical bearing seat 2. The pintles 4 may be formed integral with or secured to the side bars 3, and each is provided with interlocking means, the example here shown being an interlocking head 5 adapted to pass 50 through the opening of a strap link when

the side bar 3 is turned at an angle thereto. At the end of each side bar 3, opposite the pintle 4, is formed a substantially key-hole shaped aperture having a relatively narrow portion 6 adapted to engage the pintle 60 4 of the opposite side bar, and a relatively wide portion 7 through which the heads 5 of said pintle may freely pass.

The interlocking heads 5 may be variously formed, but I find a convenient construction is to form them with transverse extensions so as to give the substantially rectangular head shown in the drawings, lying substantially crosswise of the body of the side bar. This head, when the side bar is turned at 70 an angle to the opening in the strap link, can be passed therethrough; then through the enlarged portion 7 of the aperture in the opposed side link, and finally longitudinal shifting of the links will bring the pintle 75 into the narrow portion 6 of the side link aperture, with the head 5 interlocking on the outer wall of the side link.

To assemble the chain, the pintle 4 of one side bar is thrust through the opening of a strap link 1, and the pintle 4 of the opposite side bar of that pair is thrust through the opening of another strap link 1. The heads of both pintles are then thrust through the wide portion 7 of the apertures in the opposite side bars 3, and said side bars are moved longitudinally to cause said pintles to enter the narrow portion 6 of their respective apertures. The heads 5 of both pintles 4 will then engage the side bars 3 90 to prevent their lateral displacement, the body of the pintle taking its seat at the end of the narrow portion 6 of the aperture.

To disassemble such a chain, the pintles 4 are moved longitudinally towards each other a sufficient distance to permit their heads 5 to be shifted laterally through the wide portion 7 of their respective apertures, and the operation, as above described, for assembling, is reversed.

100 It is to be understood that I do not limit myself to the specific construction above described, as these devices may be subject to wide modification without departure from the spirit of my invention.

I claim:—

1. In a chain, a link having an elongated transverse slot at each end forming a pintle bearing at each end of the link, and a link comprising a pair of oppositely disposed 110

- similar side bars, a pintle rigidly secured to and projecting laterally from each side bar, said pintles having their free ends expanded in a transverse direction, the expanded ends of said pintles being insertable through the end slots of said first named link, when the side bars are held at an angle to the latter, each side bar having a substantially key-hole shaped aperture adapted to engage 10 in its reduced portion the projecting end of the pintle of the other side bar under the expanded portion of the said pintle for preventing relative lateral movement of said side bars.
- 15 2. In a chain, a link having an elongated transverse slot with substantially parallel walls and forming a pintle bearing at each end of the link, and a link comprising a pair

of oppositely disposed similar side bars, a pintle rigidly secured to and projecting laterally from each side bar, said pintles having their free ends expanded in a transverse direction, the expanded ends of said pintles being insertable through the slots of said first named link when the side bars 25 are held at an angle to the latter, each side bar having a substantially key-hole shaped aperture adapted to engage in its reduced portion the projecting end of the pintle of the other side bar under the expanded portion of said pintle for preventing relative lateral movement of said side bars.

In testimony whereof I have hereunto set my hand.

LAWRENCE E. BRILL.
